UNITED STATES PATENT OFFICE.

RALPH GREGORY, OF KANSAS CITY, MISSOURI, ASSIGNOR TO OIL WELL RECLAMATION COMPANY, OF CHICAGO, ILLINOIS, A CORPORATION OF DELAWARE.

OIL-WELL PUMP.

1,332,333.

Specification of Letters Patent.

Patented Mar. 2, 1920.

Application filed January 20, 1919. Serial No. 272,151.

To all whom it may concern:

Be it known that I, RALPH GREGORY, a citizen of the United States, residing at Kansas City, in the county of Jackson and State of Missouri, have invented certain new and useful Improvements in Oil-Well Pumps, of which the following is a specification.

This invention relates to oil well pumps of that class employing fluid under pressure, *i. e.*, a fluid piston, for effecting the elevation and discharge of the oil from the well, and the special object is to produce a pump having a barrel made up of sections to accommodate it to well casing of any length, means to provide a fluid-tight chamber between the casing and barrel, extending from above the level of the oil to a plane near the lower end of the casing, a check-valve to admit oil to the fluid-tight chamber and retain part of it therein in the interim between discharges of oil by the pump and a compressed air pipe for supplying pressure upon the oil in the air-tight chamber to effect the discharge of most of the oil therefrom.

A further object is to produce an oil well pump of the character set forth which performs its function efficiently, is strong and durable and is comparatively inexpensive of construction.

With these objects in view the invention consists of certain novel and useful features of construction and organization of parts as hereinafter described and claimed; and in order that it may be fully understood, reference is to be had to the accompanying drawing, in which:

Figure 1, is a central vertical section of an oil well pump constructed in accordance with my invention.

Fig. 2, is a horizontal section on the line II—II of Fig. 1.

Fig. 3, is a horizontal section on the line III—III of Fig. 1.

Fig. 4, is a horizontal section on the line IV—IV of Fig. 1.

In carrying out the said invention, the well casing 1 constitutes the shell of the pump, and secured in said casing or shell, preferably near the lower end of the same is a valve casing 2 provided with devices for preventing rotative movement of the valve casing within the shell or casing 1, the means

shown comprising a plurality of springs 3 pressing against said shell and depending 55 from the casing 2.

The chamber of the valve casing is equipped with a removable ring 4 constituting a seat for the ball valve 5 of metal or other durable material, and said ball valve fits between a 60 series of vertical guide ribs 6 having their upper ends extending inwardly at 7 to limit upward or unseating movement of the valve.

The top of the valve casing 2 is provided with a threaded opening 8 engaged by the 65 threaded lower end of the pump barrel 9 which barrel is provided at a relatively short distance above the valve casing with a plurality of perforations 10.

11 is a nut secured on the lower end of the 70 barrel within the upper part of the chamber of the valve casing, to avoid chance detachment of the barrel from the casing. Mounted loosely on the barrel is a packing disk 12, preferably of lead and provided at its periphery 75 with a depending V-shaped flange or fin 13 adapted for engagement with the upper end of the valve casing where the same is rounded, so that when sufficient pressure is brought to bear on the packing disk, the 80 flange or fin shall be spread or expanded and form a fluid-tight joint between the valve casing and the shell of the pump.

Secured upon the barrel of the pump between the perforations 10 thereof and the 85 packing disk 12, is an inverted conical packing 14 for engaging the inner edges of a series of roughened or toothed gripping jaws 15 fitting movably in vertical slots 16 in a cylindrical cup 17 screwed at its lower 90 end upon the pump barrel and adapted for applying the pressure hereinbefore mentioned, upon the packing disk to expand or spread the flange thereof, it being noticed that the gripping jaws 15 are provided at 95 their upper ends with upstanding stops 18 and at their lower ends with depending stops 19, for guarding against any possibility of the wedge 14 forcing the said jaws completely through the slots 16 of the 100 cup 17.

Secured upon the upper end of the barrel 9 preferably at or near the level of the oil within the well, is a cylindrical coupling 20 provided at its lower end with a chamber 21 in communication with said barrel, and

with the lower end of the discharge pipe 22 of the pump, said discharge pipe being screwed at its lower end to and within the coupling and extending up through the 5 chamber 23 thereof to a point exterior to the well, as customary. The coupling is provided at the upper end of chamber 23 with an internal socket 24 for the reception of a nut 25 secured upon the discharge pipe, and 10 the upper end of the coupling like the valve casing 2, is rounded for the spreading or expansion of the depending annular flange or fin 27 of a compressible packing disk 26 of lead or the like, said packing disk fitting 15 loosely on discharge pipe 22 below a collar 28 rigidly secured on said pipe, and adapted for applying downward pressure upon the packing disk to cause the same to spread or expand the flange or fin of the same and seal 20 the joint between the coupling and the shell of the pump.

At or near the level of the oil in the pump, the coupling is provided with a cross tube 29, the passage thereof communicating 25 with the space between the barrel and shell of the pump, and at the lower end of a vertical tube 31 for supplying compressed fluid, for effecting the discharge of oil from the pump; said tube extending down 30 through the discharge pipe 22 and being screwed at its lower end in a threaded opening in the cross tube of the said coupling. A check valve 32 is provided in the barrel 9 just above the perforations 10 to prevent oil 35 standing above the said valve from seeking its natural level when the air pressure is cut off.

In assembling this pump the cup 17 is first placed on the lower end of the pump 40 barrel. The packing disk 12 is then slipped on said barrel from below the cup, and then the valve casing is screwed upon the lower end of the barrel and into the nut 11 fitted in said casing through the lower end of the 45 same. The ball valve is then secured therein by the fitting of the ring 4 in place.

The gripping jaws 15 are then fitted in the cup and the wedge 14 slipped down upon the barrel and within the cup and secured 50 rigidly to the former.

The coupling 20 is then screwed upon the upper end of the barrel, and the discharge pipe 22, equipped with the collar 25, is slipped down into the coupling and screwed 55 at its lower end to the latter as shown, the upper end of the coupling being removable to permit of the insertion of the collar. The packing disk 26 is then slipped down upon the pipe 22, and the clamping collar 28 is 60 secured upon said pipe. The air tube is then fitted down through the discharge tube and screwed to the coupling as shown.

As will be understood the distance between the cup 17, which will preferably be 65 near the lower end of the casing, and the

air passage 30, may be hundreds of feet as it is preferable that said air tube shall be slightly above the level of the oil.

When the parts are fitted in the casing as explained, power is applied in any suitable 70 manner to lift the discharge pipe,—at this time unthreaded from the coupling,—until the collar 25 is fitted in the socket 24. While holding the parts elevated, power is applied to turn pipe 22 and hence barrel 9, to screw 75 the latter downward in the valve casing,—which as stated is prevented from rotation by the fastening devices 3,—to cause the cup 17 to move downward upon and apply sufficient pressure on the disk 12 to cause the 80 same to seal the joint between the valve casing and the shell, further rotation of the barrel then causing the wedge 14 to force the jaws 15 outward against the shell and thus guard against upward movement of 85 the cup and the consequent unsealing of said joint. The discharge pipe is then lowered to dispose the collar 28 close to the packing disk 26 and the lower end of said pipe in engagement with the internally threaded 90 portion of the coupling 20, and then the pipe is turned to screw it into the said threaded portion of the coupling and incidentally cause the collar 28 to apply downward clamping pressure upon the disk 26 95 and thus expand the same as explained, and seal the joint between the upper side of the coupling and the shell or casing 1.

It will thus be seen that a sealed chamber is provided within the shell 1 extending 100 from one sealing disk to the other, and that said distance will be determined according to the head of oil, with the disk 26 preferably slightly above the level of the oil so that when compressed air is supplied 105 through the pipe 31 and passing through passage 30 to exert pressure on the column of oil in the shell, but little waste space for the admission of air will be provided. It will be apparent that when there is no pressure on the oil the latter will seek its level 110 within the shell and barrel, raising the valve 5 and passing up into the barrel and thence through the perforations 10 into the shell between the sealed points thereof. When 115 the compressed air is supplied but little pressure will be required at first to start the elevation of the oil through the barrel, chamber 21 of the coupling and the discharge pipe 22, the pressure required increasing 120 as the oil level in the shell is lowered. When said level nearly reaches the perforated portion 10, the air is cut off, and that above the oil permitted to pass back up through the tube 31 and be either employed 125 in useful work or discharged into the atmosphere or it may be withdrawn through tube 31 with power to create a partial vacuum in the shell and barrel to facilitate the recharging of the well with oil, the production 130

of oil being increased by this course, not only because the oil will attain its natural level more quickly but also because the lack of atmospheric pressure resistance will result in the oil rising to a higher than natural level. All succeeding operations will be repetitions of those described.

From the foregoing it will be apparent that I have produced a pump utilizing the 10 gravitation force of the column of oil of equal height to a second column of oil to aid in the discharge of the latter, and in which a vacuum may be produced for increasing and cheapening production, and 15 while I have illustrated and described the preferred construction, it is to be understood that I reserve the right to make all changes falling within the principle of construction and mode of operation involved and the 20 spirit and scope of the appended claims.

The structure of the air supply pipe passing through the discharge pipe and the coupling uniting the barrel, discharge and air pipes, disclosed but not claimed herein, is 25 claimed in combination with the barrel, casing and valves in a patent issued to me October 7th, 1919, No, 1,317,921, the application for which patent was copending with the present application.

30 I claim:

1. A pump comprising a shell extending down into a body of liquid such as oil in a well, a barrel in the shell, having a fluid-tight connection with the shell and in communication at a higher point therewith, a check valve adapted when unopposed to permit oil to pass upward into the barrel from a point below the fluid-tight connection, a discharge pipe communicating with the 35 barrel above the higher point of communication therewith of the said shell and having a fluid-tight connection with the shell, and means for supplying fluid under pressure to the shell upon oil standing therein to force 40 upward from the discharge pipe oil standing in the barrel from above the point of communication thereof with the shell or for enabling fluid under pressure to escape from that portion of the shell between the points where the same is in fluid-tight connection with the barrel and the discharge pipe.

2. A pump comprising a shell extending down into a body of liquid such as oil in a well, a barrel in the shell and in communication at a higher point therewith, a check valve adapted when unopposed to permit oil to pass upward into the barrel from a point below the fluid-tight connection, a discharge pipe communicating with the barrel above 55 the said higher point of communication therewith of the said barrel and having a fluid-tight connection with the shell, and a tube extending through the discharge pipe and communicating with the shell between the points where it has fluid-tight connec-

tions with the said discharge pipe and the said barrel.

3. A pump comprising a shell extending down into a body of liquid such as oil in a well, a check valve within and having a 70 fluid-tight connection with the lower end of the shell and adapted to open when unopposed, a barrel within the shell and communicating at its lower end with the valve chamber, and provided with a perforation 75 establishing communication with the shell above the point where the same has fluid-tight connection with the valve casing, a discharge pipe communicating with the barrel above the higher point of communication 80 therewith of the said shell and having a fluid-tight connection with the shell, and means for supplying fluid under pressure to the shell upon oil standing therein to force upward from the discharge pipe 85 oil standing in the barrel from above the point of communication thereof with the shell or for enabling fluid under pressure to escape from that portion of the shell between the points where the same is in fluid-tight connection with the barrel and the discharge pipe.

4. A pump comprising a shell extending down into a body of liquid such as oil in a well, a check valve within and having a 95 fluid-tight connection with the lower end of the shell and adapted to open when unopposed, a barrel within the shell and communicating at its lower end with the valve chamber, and provided with a perforation 100 establishing communication with the shell above the point where the same has fluid-tight connection with the valve casing, a discharge pipe communicating with the barrel above the higher point of communication 105 therewith of the said barrel and having a fluid-tight connection with the shell, and a tube extending through the discharge pipe and communicating with the shell between the points where it has fluid-tight connections 110 with the said discharge pipe and the said barrel.

5. A pump comprising a shell extending down into a body of liquid such as oil in a well, a barrel in the shell, having a fluid-tight connection with the shell and in communication at a higher point therewith, a check valve adapted when unopposed to permit oil to pass upward into the barrel from a point below the fluid-tight connection, a discharge pipe in the shell, a coupling connecting the discharge pipe and barrel and having a fluid-tight connection with the shell, and means for supplying fluid under pressure to the shell upon oil standing 120 therein to force upward from the discharge pipe oil standing in the barrel from above the point of communication thereof with the shell or for enabling fluid under pressure to escape from that portion of the shell be- 125 130

tween the points where the same is in fluid-tight connection with the barrel and the discharge pipe.

6. A pump comprising a shell extending down into a body of liquid such as oil in a well, a barrel in the shell, having a fluid-tight connection with the shell and in communication at a higher point therewith, a check valve adapted when unopposed to permit oil to pass upward into the barrel from a point below the fluid-tight connection, a discharge pipe in the shell, a coupling connecting the discharge pipe and barrel and having a fluid-tight connection with the shell, and a tube extending through the discharge pipe and communicating with the shell between the points where it has fluid-tight connections with the said discharge pipe and the said barrel.
- 10 7. In a pump, a shell extending downward into a body of liquid, a check valve secured non-rotatably to the shell and a valve normally closing communication between the casing and the lower part of the shell, a barrel in communication with the chamber of the valve and in communication with the shell at a higher point than the point of communication of the former with the said casing, a compressible disk around the barrel above the casing, and means to clamp the disk upon said casing and against said shell to seal the joint between them.
- 15 8. In a pump, a shell extending downward into a body of liquid, a check valve secured non-rotatably to the shell and a valve
- 20 normally closing communication between the casing and the lower part of the shell, a barrel in communication with the chamber of the valve and in communication with the shell at a higher point than the point of communication of the former with the said casing, a compressible disk around the barrel above the casing, and means actuated by rotation of said barrel to cause said disk to seal the joint between said casing and the shell.
- 25 9. In a pump, a shell extending downward into a body of liquid, a check valve in the shell comprising a casing non-rotatably arranged in the shell and a valve normally closing communication between the casing and the lower part of the shell, a barrel bearing a threaded relation to said casing and communicating with the chamber thereof, a slotted cup fitting in the shell and having an aperture in its bottom through which the barrel extends, a compressible washer fitting around the barrel between the cup and casing, and adapted when the barrel is turned to effect approaching movement between the cup and casing, to be compressed and caused to seal the joint between the shell and casing, gripping jaws fitted in the slotted cup, and a wedge secured to the barrel and adapted when the latter is screwed downward, to engage and force said jaws outwardly into gripping engagement with said shell.
- 30 10. In a pump, a shell extending downward into a body of liquid, a check valve secured non-rotatably to the shell and a valve
- 35

normally closing communication between the casing and the lower part of the shell, a barrel in communication with the chamber of the valve and in communication with the shell at a higher point than the point of communication of the former with the said casing, a compressible disk around the barrel above the casing, and means actuated by rotation of said barrel to cause said disk to seal the joint between said casing and the shell.

9. In a pump, a shell extending downward into a body of liquid, a check valve in the shell comprising a casing non-rotatably arranged in the shell and a valve normally closing communication between the casing and the lower part of the shell, a barrel bearing a threaded relation to said casing and communicating with the chamber thereof, a slotted cup fitting in the shell and having an aperture in its bottom through which the barrel extends, a compressible washer fitting around the barrel between the cup and casing, and adapted when the barrel is turned to effect approaching movement between the cup and casing, to be compressed and caused to seal the joint between the shell and casing, gripping jaws fitted in the slotted cup, and a wedge secured to the barrel and adapted when the latter is screwed downward, to engage and force said jaws outwardly into gripping engagement with said shell.

In testimony whereof I affix my signature.
RALPH GREGORY.
